UNITED STATES PATENT OFFICE.

JOHN PETERSELKA, OF CHICAGO, ILLINOIS.

ILLUMINATING DEVICE FOR BAKERS' OVENS.

SPECIFICATION forming part of Letters Patent No. 361,714, dated April 26, 1887.

Application filed January 31, 1887. Serial No. 226,053. (No model.)

To all whom it may concern:

Be it known that I, JOHN PETERSELKA, a citizen of the United States of America, residing at Chicago, in the county of Cook and State of Illinois, have invented certain new and useful Improvements in Illuminating Devices for Bakers' Ovens, of which the following is a specification, reference being had therein to the accompanying drawings.

10 This invention has for its object to provide a device for automatically controlling the gas-jet illuminating the interior of a baker's oven in a manner that the gas is turned on full only while the working-door is opened for inspection or for inserting or removing the bakings, whereby a large amount of illuminating-gas will be saved; and it consists in the construction and combination of parts, hereinafter set forth and claimed.

20 In the accompanying drawings, Figure 1 represents a front elevation of a baker's oven having a vertically-sliding door with my improvements attached; Fig. 2, a sectional plan of the same, and Fig. 3 an elevation of the 25 gas-cock as constructed for my purpose. Fig. 4 represents a front elevation of a baker's oven having swinging doors with my improvements attached, and Fig. 5 a sectional plan of the same.

30 Corresponding letters in the several figures of the drawings designate like parts.

In Figs. 1 and 2, A denotes the oven; B, the opening affording admittance to the same, and closed by door C, vertically sliding between 35 guides a, and counterbalanced by a weight, D, connected by a rope or chain, c, passed over sheaves d. To one side of this opening B, in the front wall of the oven, is another opening, E, in the usual manner, which opening, on the 40 inner face of the wall, is closed by a glass plate, e, and in front of this glass plate is the gas-burner F, and the pipe f, leading to this burner, has interposed a cock, G, of the usual construction, excepting that the plug of the 45 same, instead of having a flattened handle, has an eyed knob, g, for inserting and securing therein by a set-screw a lever, H. Against door C is fastened by screws the flange of a tubular bracket, I, having a squared opening,

through which is passed a square rod, h, ad- 50 justably secured therein by a set-screw, i, tapped in tube I, and by a collar, J, having set-screw j. At one end this rod h has pivotally secured a fork that engages lever H.

By raising door C the lever H will be swung 55 upward, thereby turning the plug g to open cock G, and with closing the door again the lever H will be swung to close the cock.

In Figs. 4 and 5 the opening B of oven A is closed by swinging or hinged doors L L'. In 60 this case the fork K is secured to one of the doors L, and the lever H, supported therein, is bent to the proper curve, that when such door L' is swung open the lever H will be swung 65 upward, thereby opening the cock G; and for closing such cock a weight, M, is secured upon lever H, which by its gravity will swing the lever downward again when shutting door L'.

With either a vertically sliding or swinging door the parts are so adjusted that when the door is closed the cock is not quite closed, but to allow just sufficient gas to pass through that a small flame will be burning continuously, the size of which flame increases with opening 70 the door, while for turning off the gas entirely 75 the lever H is disconnected from fork K, and is swung to the opposite side of opening E.

What I claim is—

1. The combination, with the moving door of a baker's oven, having a fork, as described, 80c of a gas-burner for illuminating the interior of the oven, and a lever rigid with the plug of the gas-cock and passing loosely through the said fork on the door, as set forth.

2. As an attachment to a baker's oven having 85 vertically-sliding door C and gas-burner F, with cock G, the laterally-adjustable bar I, secured to such door and provided with pivotal fork K, and of lever H, secured to plug g of cock G, the whole being constructed and arranged to operate substantially as described, 90 for the purpose specified.

In testimony whereof I affix my signature in presence of two witnesses.

JOHN PETERSELKA.
